UNITED STATES PATENT OFFICE.

JOSEPH H. MELICK, OF NEW GERMANTOWN, NEW JERSEY.

IMPROVEMENT IN VAPOR-BURNERS.

Specification forming part of Letters Patent No. 92,537, dated July 13, 1869.

To all whom it may concern:

Be it known that I, JOSEPH H. MELICK, of New Germantown, in the county of Hunterdon and State of New Jersey, have invented a new and Improved Vapor-Burner for Lamps; and I do hereby declare that the following is a full, clear, and exact description thereof, which will enable others skilled in the art to make and use the same, reference being had to the accompanying drawings, in which—

Figure 1 represents a vertical central section of my improved vapor-burner. Fig. 2 is a vertical section of a modification of the same.

Similar letters of reference represent corresponding parts.

This invention relates to certain improvements on that class of lamp-burners in which the vaporized hydrocarbon escapes through small apertures from the burner, the jets thus produced being ignited.

The object of the present invention is to so construct them that the light may be extinguished without producing any smoke.

The vapor-burners now in use cannot be adjusted for larger or smaller lights, and can only be extinguished by blowing out the flame. Much smoke is produced by the latter process, and a consequent disagreeable smell.

A, in the drawing, represents my improved burner. This is made of a circular top plate, *a*, and conical base *b*, the latter projecting from an upright tube, *c*.

The plate *b* has a series of very fine apertures, through which the gas can escape. The lower end of the tube *c* has a flange, *d*, formed on it, which serves as a handle for turning and raising the burner on the wick-tube *B* of the lamp.

The wick in the tube *B* raises the liquid,

which is vaporized by the heated plates of the burner, and escapes in jets through the apertures of the same to form a series of flames. When the burner is lowered to a certain degree there is a certain compression produced on the gases, which will cause the escape to be more rapid and the flames to be larger. Above and below this point the flames will become smaller.

By means of the button *d* the burner can be readily raised or lowered on the wick-tube to produce a stronger or less light.

The top plate of the burner carries an upward-projecting cap, or rather socket, *e*, which, when the burner is lowered, will fit over and entirely close and cover the wick-tube. The same cap may also be made to project from the under side of the plate *a*, as in Fig. 2, to fit into the top end of the wick-tube. The same cap may also be made to project from the under side of the plate *a*, as in Fig. 2, to fit into the top end of the wick-tube, for the same purpose, to the same effect. When the wick-tube is thus closed, by letting down the burner the light will be extinguished, and all escape of gas and smoke most effectually prevented.

Having thus described my invention, what I claim as new, and desire to secure by Letters Patent, is—

The upward or downward projecting cap *e* formed on the vapor-burner, substantially as described, to close effectually over or into the wick-tube, as set forth.

JOSEPH H. MELICK.
